UNITED STATES PATENT OFFICE

EDWARD H. FRICKEY, OF PASADENA PARK, MISSOURI

CRUSHER

Application filed October 5, 1928. Serial No. 310,452.

This invention relates to crushers, and with regard to certain more specific features to crushers for such materials as limestone, shale, iron, ore, coal, gypsum, asphalt rock and similar materials which may contain 5 moist impurities such as clay or mud.

Among the several objects of the invention may be noted the provision of a crusher having movable breaker plates adapted to follow 10 the peripheral movement of crushing members throughout a substantial arc whereby a crushing action may be prolonged. Other objects will be in part obvious and in part pointed out hereinafter.

15 The invention accordingly comprises the features of constructions, combinations of elements, and arrangements of parts which are exemplified in the structure hereinafter described, and the scope of the application of 20 which will be indicated in the following claims.

In the accompanying drawings, in which are shown several of various possible embodiments of this invention,

25 Fig. 1 is a right side elevation of the crusher;

Fig. 2 is a front elevation;

Fig. 3 is an ideal longitudinal section taken approximately on the line 3—3 of Fig. 2;

30 Fig. 4 is a view similar to Fig. 3 showing an alternate form of the invention; and,

Fig. 5 is a fragmentary view showing certain chain breaker plate details.

Similar reference characters indicate 35 responding parts throughout the several views of the drawings.

Referring now to the drawings there is illustrated at 1 a frame comprised of side castings 3, a cover 5 and a hopper chute 7.

40 Forwardly bolted at 9 between the two side castings 3, is a cross channel beam 11 (see Fig. 4). This channel beam 11 serves to tie the side castings together at the forward end of the crusher. Ahead of said channel beam

45 11 is bolted another cross beam or brace casting 10 bolted sidewardly at points 12. This casting 10 also aids in holding the frame side castings 3 together. Rearwardly a frame 13 serves the same purpose. The frame 13 has 50 its central opening normally closed by a door

15 which may be opened for purposes of inspection when occasion demands. It is to be understood that the beam 11 may be dispensed with, under certain conditions.

The cover 5, itself an assembly of component castings serves to close the device and tie the end castings together at their upper portions.

55 The side castings 3, the frame 13 including its door 15, and the cover 5 serve to enclose a 60 rotating set of hammers 17 mounted between discs 19. The disc faces are machined to receive the hammers between them and are provided with throughbolts 21 for tightening the hammers. Other holes 23 in the discs 65 permit adjustment of each set of hammers as wear on said hammers takes place. The adjustment is radial so that as the hammers wear shorter, compensation may be permitted.

70 The discs and hammers are mounted upon a shaft 25 running cross-wise of the machine. This shaft is borne in ring-oiled bearings 27 at each side of the device. The bearings are cast with the end castings and are of generous 75 proportions as is the whole machine. On the left end of the shaft, and outside of the machine is borne a fly-wheel 29, and on its right end a driving coupling 31.

77 Cradled below the rotary hammers 17 are 80 cage bars or gratings 33, cast en bloc (see Fig. 3). They are held in position by means of bolts 35 and cage liners 37. The liners are bolted to the side castings 3 and serve as end supports for the cage bars. They 85 also protect the surfaces to which they are bolted from abrasion. These bars serve to permit only a material which has been crushed down to a proper size to pass out of the base of the machine.

90 At the ends of the hammer-disc assembly, or rotor, are placed end liners 39. These are bolted to the end-casting 3 and cover 5 and serve as renewable safeguards against abrasion of said parts. The chute 7 is lined 95 with liners 14 at points subjected to abrasion.

Forwardly of the machine, and on the upper corners of the side castings 3 are fastened guide castings 41 (Figs. 1 and 2). These castings 41 are provided with rear-

wardly and downwardly sloping guide slots 43.

Adjustable bearings 47 are slidably held in the slots 43. These bearings are suitably held in an adjustable position by means of underslung saddle members 49 upon which said bearings rest. The members 49 are countersunk into the bearings 47 and prevent side-ward motion of said bearings. The members 49 are held in position by a pair of adjusting bolts 51.

Mounted in and between the bearing blocks 47 is an upper cross-shaft 45 upon which is mounted a plurality (four shown in Fig. 2) of supporting rolls 55. The rolls 55 may be varied in number and position to suit certain types of breaker plate chains to be mounted thereon.

A lower cross shaft 57, similar to the upper cross shaft 45, extends laterally between the side castings 3. It is mounted in adjustable bearing blocks 16 at each side of the machine. The blocks 16 are slidably arranged in substantially horizontal guides 18, formed in sidewardly placed castings 20. The castings 20 may either be formed integrally with the side castings 3 or be bolted thereto. It is obvious that the shaft 57 may be moved forwardly or rearwardly by sliding the bearing blocks 16 in their guides 18. Substantially horizontal elongated passages 22 (see Fig. 1) are formed in the side castings 3 in order to permit said movement of the lower cross shaft 57. A proper tongued and grooved formation of the bottoms of the guides prevents sidewise motion of the blocks and yet permits their removal at one end of their travel. Each of a pair of levers 28 is pivoted to a side casting 3 at the upper front portion of said casting, that is, beneath the guide casting 41. Each reaches downwardly and embraces a portion of its respective shaft 57 at an opening 26. The openings 26 are of such length, that if the levers 28 be swung forwardly or rearwardly the blocks 16 may traverse their complete predetermined path. Each opening 30 permits ample swing of its corresponding lever 28.

It is obvious at this stage of the description, that by swinging the levers 28 upon their pivot rod 2, that the lower cross shaft 57 may be moved forwardly or rearwardly of the crusher.

In order to swing the levers 28 on their pivot rods 2, sideward adjusting rods or bars 32 are pinned to bosses 34 formed with the levers 28. A through-bolt or shaft 36 serves to pin each bar 32 to its lever 28 and nuts are provided on the bolt ends whereby the bars 32 and levers 28 may be drawn tightly together after an adjustment is made. The levers 28 and bars 32 are drawn against the side castings 3. The bars 32 pass forward of the machine in under the bearings 27, and through lugs 38 formed integrally with the

rearward end of the machine. These side bars may be adjusted by means of nuts and lock nuts 50 so that they may govern the swing position of the levers 28 and other parts to be described. Fig. 3 shows one of two slots 42 formed in the side castings 3 which accommodate the forward and rearward motion of the clamping through-bolt or shaft 36. The shaft 36 reaches laterally across the machine (Figs. 1 and 3), as does the pivot rod 2.

Reference to Fig. 3 indicates that the cross shaft 57 has fastened thereto sprockets 59 placed just within the limits of the side castings 3.

Over the sprockets 59 of the lower shaft 57 and the supporting rolls 55 of the upper shaft 45 is placed a belt or chain 67 comprising links or breaker plates 69 formed of solid manganese or other wear and impact resisting material (see Figs. 3, 4 and 5).

Each link 69 comprises a stagger shaped bar adapted to be pinned to the next bar and having means formed to cooperate with the sprockets 59 such that said sprockets can effect driving of the chain of breaker plates.

In the above description, certain detailed features have not been set out, inasmuch as they are set out more particularly in Patent No. 1,605,181, dated November 2, 1926.

The improvement herein set out comprises the addition of a sprocket shaft 71 carrying sprockets 73 adapted to receive the chain of breaker plates in driving relationship. It will be noted from Fig. 3 that the sprockets 73 are so positioned with respect to the periphery of the hammer that the chain is juxtaposed near the hammer elements over a substantial arcuate portion, instead of merely tangentially as has been the case before. The liners 39 serve to guide the chain so that it does not engage the hammers. The lower reach 75 of the chain between the sprockets 73 and 59 does not require guiding in the form of Fig. 3 because said reach is short.

The advantage of the above construction is that the breaker plates traverse a path which permits longer juxtaposition of breaker plates and hammers so that an increase crushing effect is obtained with the advantage of having movable breaker plates adapted to draw material into the hammer paths.

The linked chain 67 and the hammers 17 form the crushing elements of this machine. The links cover the width of the hammer rotor in projection. In order to withstand the attendant impact of the crushing operation the chain 67, or breaker plates 69, are backed by a suitable rugged platen 81. This platen 81 is pivoted to the end castings 3 by the said pivot rod 2 which forms the pivots for the outside adjusting arms 28 (see Figs. 2 and 3). It backs the chain of breaker plates at the point of impact. It may be ad-

justed to different required degrees of slope of the breaker plates or to different degrees of wear in said members by means of the said shaft 36 which passes through said slots 83 in flanges 85 of the platen and through slots 42 in the side castings 3. Outside of the side castings 3, it should be remembered, the shaft 36 serves normally to clamp the levers 28 and rods 32 together and to the said castings 3. Hence it is clear that when the lower shaft 57 is adjusted to position by means of the rods 32 and levers 28, after loosening shaft 36, that the backing platen 81 is automatically adjusted by means of the said rod 36.

In Fig. 2 is illustrated the driving means applied to shaft 57. At the left side of the machine the shaft 57 extends outwardly to receive a splined universal joint 111. The joint 111 is provided with a drive shaft 113. The shaft 113 is in turn driven through another splined universal joint 115 by a primary drive shaft 117 emanating from a suitable driving source.

The shaft 57 is driven in a clockwise direction as viewed in Figs. 1 and 3. It is obvious that, due to the universal drive described, that the shaft 57 may be driven in any of its adjusted positions and thereby drives the breaker plate chain downwardly at the point of impact. The hammers 17 rotate counter-clockwise as viewed in Figs. 1 and 3. Their linear speed at the crushing point is preferably substantially higher than that of the moving plates, whereby material is carried down to the grates.

The operation of the machine is as follows:

Material such as lump rock is fed into the hopper 7. Gravity carries it downward on the sloping breaker plates into the paths of the rapidly rotating hammers 17. These hammers impact the lumpy material against the slowly and downwardly moving breaker plate chains, thereby breaking most of the material down to a size small enough to pass the cage bars 33. That which has not been broken small enough can not pass the cage bars and consequently goes around with the hammers for a second crushing. The liners 40 and 37 protect the frame against wear. The breaker plates of course transmit the force of the blow given to them, to the backing platen 81. Although the upper reach of chain between sprockets 59, 73 is not provided with a backing platen, yet this is not a disadvantage, because the primary impact does not occur at this region. It is however clear that a backing platen might be arranged at this region.

One advantage of moving the breaker plates is to carry the material down into the hammers.

Another advantage of moving the breaker plates is to equalize wear on them. The advantages of having the adjustments de-

scribed, for purposes of grading material and to take up wear are obvious. The improved means for making these adjustments saves time in making them for two such adjustments may be made at once and while the machine is in motion. The cooperation of the universal drive permits such adjustments.

In Fig. 4 is shown a modified form of the machine in which the grating 33 is eliminated and the shaft 71 is re-positioned so that a greater arc of juxtaposition is had between the chain and the hammers. In this case liners 119 are added between the chain reaches on each side of the casing so as to aid in guiding the chain and supporting it against the grinding action. In this modified form the material is crushed primarily at the region of the backing plate 81 and thereafter crumbled by rolling along the chain. Inasmuch as the upper reach of the chain forms a hollow region 121, the material tends to roll back after the center line of the machine is passed, thus enhancing the crushing effect, but at the same time the movement of the chain prevents gathering of particles at the hollow portion.

In view of the above, it is believed that the various features of this invention will be clear without further elaboration, and it will be seen that with the apparatus herein described, the several objects of the invention are achieved and other advantageous results attained.

As many changes could be made in carrying out the above construction without departing from the scope of the invention, it is intended that all matter contained in the above description or shown in the accompanying drawings shall be interpreted as illustrative and not in a limiting sense.

I claim:

1. In a crusher, the combination of rotary crushing elements, a chain of movable impact plates cooperating therewith and adapted to receive the impact of blows of said elements on material being crushed, means backing said chain at the point of impact, said impact plates moving in juxtaposition to said elements over an arc.

2. In a crusher, the combination of rotary crushing elements, movable impact plates cooperating therewith, means for moving said plates in a substantially straight line tangentially toward the periphery of said crushing elements, a platen backing said impact plates at the point of tangency, and means for moving said impact plates in juxtaposition to said element over an arc beyond the point of tangency.

3. In a crusher, the combination of rotary crushing elements, movable impact plates cooperating therewith, means for moving said plates in a substantially straight line tangentially toward the periphery of said crushing elements, a platen backing said impact

plates at the point of tangency, means for moving said impact plates in juxtaposition to said element over an arc beyond the point of tangency, and supporting and guiding means located endwise of said impact plates where they move arcuately.

4. In a crusher, the combination of rotary crushing elements, movable impact plates cooperating therewith, means for moving said plates in a substantially straight line tangentially toward the periphery of said crushing elements, a platen backing said impact plates at the point of tangency, means for moving said impact plates in juxtaposition to said element over an arc beyond the point of tangency, supporting and guiding means located endwise of said impact plates where they move arcuately, and supports for the impact plates located at the ends thereof and at the said point of tangency.

5. In a crusher, the combination of rotary crushing elements, a chain of movable impact plates cooperating therewith and adapted to receive the impact of blows of said elements on material being crushed, means backing said chain, said impact plates moving in juxtaposition to said crushing elements over an arc, and arcuately positioned grating extending the arc of said impact plates.

6. In a crusher, the combination of rotary crushing elements, a chain of movable impact plates cooperating therewith and adapted to receive the impact of blows of said elements on material being crushed, said impact plates moving in juxtaposition to said crushing elements over an arc, and arcuately positioned grating extending the arc of said impact plates.

In testimony whereof, I have signed my name to this specification this 2nd day of October, 1928.

EDWARD H. FRICKY.
